US00D559249S

(12) **United States Design Patent** (10) Patent No.: **US D559,249 S**
Takei (45) Date of Patent: **** Jan. 8, 2008**

(54) **PORTABLE HARD DISK DRIVE**
(75) Inventor: **Yutaka Takei**, Tokyo (JP)
(73) Assignee: **Sony Corporation**, Tokyo (JP)
(**) Term: **14 Years**
(21) Appl. No.: **29/263,346**
(22) Filed: **Jul. 21, 2006**
(51) LOC (8) Cl. **14-02**
(52) U.S. Cl. **D14/356**
(58) **Field of Classification Search** **D14/137, D14/156, 167, 240, 242, 299, 348, 356, 384-5, D14/402, 432-435, 496; 257/315; 439/518, 439/139, 141, 144, 140, 638; 365/63, 131; 710/74, 62; 361/685-6**

(57) **CLAIM**

The ornamental design for a portable hard disk drive, as shown.

DESCRIPTION

FIG. 1 is a front right top perspective view of a portable hard disk drive showing my new design;

FIG. 2 is a front left top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
